UNITED STATES PATENT OFFICE

1,962,810

METHOD OF AND MACHINE FOR
MANUFACTURING CIGARSErnst Ruben Dahlström, Stockholm, Sweden, as-
signor to Aktiebolaget Formator, Stockholm,
Sweden, a Swedish joint-stock company

Application October 30, 1931, Serial No. 572,154

7 Claims. (Cl. 131—5)

The present invention relates to such cigar machines, in which bunches are treated in a wrapping device, whereby a finished product is obtained. In such machines there is generally 5 a cutting device for wrappers, which latter are to be used for the manufacture of said finished product. It also often occurs that the bunch producing device is arranged in proximity to the cigar machine or even that a device for treating the bunches, that is, a buncher, is combined 10 with the rest of the cigar machine.

Two operators are needed for the attendance of such a machine, whereas one of them handles the bunching and the other manufactures the 15 finished cigars, that is, puts tobacco leaves on a wrapper cutting device, the wrappers then being automatically transported to a wrapping device, where the bunches, which are fed forward from the buncher, are provided with such 20 wrappers. The finished cigar is then automatically transferred to a place, where it is collected by the one operator, who executes the wrapping operation. In the meantime, the operator executing the bunching is occupied with the putting 25 of bunches into the moulds, in which said bunches are pressed and formed, before they are transferred to the wrapping mechanism.

It may occur that the operator who executes 30 the wrapping, that is, puts tobacco leaves on the cutting device, is delayed in her work, because a great part of the tobacco leaves to be cut are defective and consequently after having been placed on the cutting device, where the defects 35 are most easily observed, have to be exchanged for new ones, while the bunches because of a very simple shape can very easily be placed in the pressing moulds intended for them. The result will evidently be that while the operator 40 at the wrapping device will find it difficult to have time to collect the finished product, the operator at the buncher cannot give her full capacity of work. On the other hand, should it happen that the bunches have an especially pec- 45 cular shape the placing of said bunches in the moulds will be considerably more difficult, and if at the same time all or almost all the wrappers are correct, the work of the operator occupied at the wrapping mechanism will evidently be 50 facilitated. The work of the other operator will at the same time be more difficult, and the capacity of work of the operator at the wrapping and cutting device cannot be fully used.

This disadvantage is eliminated by the present 55 invention. The invention is principally char-

acterized by the fact that the finished product that has not been picked up at the primary, that is, the hitherto usual receiving place, is transferred to a second receiving place, where it is 60 collected.

A preferred embodiment of the invention is shown in the accompanying drawings.

Fig. 1 shows a vertical side elevation of a device according to the invention and intended for the method according to the invention. 65

Fig. 2 shows a horizontal plan view of the same device.

Fig. 3 shows a vertical end elevation of the proper wrapping and bunching machine seen from the right side in Figs. 1 and 2. 70

Fig. 4 shows a detail of the device in a larger scale.

On a frame 1 is arranged a bunch producing device 2 diagrammatically shown in the drawings, as the constructive development of the 75 same forms no part of the invention. The tobacco, of which the bunches are produced is taken from a container 3. The wrapping machine is arranged on a frame 4 and consists among other things of a buncher consisting of 80 two rollers 5 and 6 provided with moulds, the shape of which is corresponding to the shape of the finished cigar. The rollers are arranged to rotate intermittently.

A plunger 7 is arranged to project in the 85 roller 5 through notches 8 into a mould 9, which for the moment is in front of a mould 10 in the roller 6. Another plunger 11 is arranged vertically in the roller 6 in such a manner that it can as the plunger 7 project through notches 12 90 and the mould 13, which for the moment is at the top of the roller 6. For that purpose the plunger 11 is actuated by an eccentric disc 14 fixed on a rotating shaft 15, whereby the plunger is imparted vertical reciprocating movements. The plunger 7 is actuated in the same 95 way as the plunger 11 to make horizontal reciprocating movements.

An arm 16 is arranged to swing together with a shaft 17 connected to a mechanism, which 100 imparts to the shaft reciprocating swinging movements. This mechanism is not shown in the drawings, as its constructive development forms no part of the invention. The arm 16 is provided with double grippers 18 and 19. On 105 the frame 4 is further arranged a wrapping mechanism 20, which is only shown diagrammatically, as its constructive development forms no part of the invention. Near the wrapping mechanism 20 is a cutting device 21 of known 110

design arranged. An arm 22 provided with a leaf carrier 23 is connected to a shaft 24, driven intermittently from any suitable power source, so that the arm can swing the leaf carrier to 5 and fro between the cutting device 21 and the wrapping device 20.

On a bracket are journaled in bearings 25 and 26 shafts 27 and 28 with a driving roller 29 and an idle roller 30, over which runs a belt 10 31. The shaft 27 is provided with a chain wheel 32, over which runs a chain 33, which is driven by a pinion 34, fixed on a shaft 35, which is coupled by means of a gear to a suitable driving motor 36. A cup 37 is arranged at the end of 15 the belt 31 near the buncher. The rollers 29 and 30 rotate clockwise. The place for the operator handling the buncher is numbered 38 and the place for the operator executing the cutting of tobacco leaves for producing wrappers 20 is numbered 39.

The embodiment of the device now described according to the invention works and is attended in the following manner:

When a bunch is produced at the bunch producing device 2 it is inserted by the operator placed at 38 in a mould 40 at the top of roller 5. During the intermittent rotation of said roller, the bunch finally reaches the position 9 shown in Fig. 4 just in front of the plunger 7, 30 which pushes the bunch out from its mould 9, so that it is brought to and pressed into the mould 10 in the roller 6 just in front of the plunger. During this transferring of the bunch, rollers 5 and 6 are at a standstill. The bunch 35 follows the stepwise rotation of the roller 6 and finally attains the position, which is marked by 13 in Figs. 2-4. When the rollers for a short moment are at a standstill, the plunger 11 projects through the mould 13 and lifts the bunch 40 to the position, shown in Fig. 4. In the meantime, the arm 16 swings from the wrapping device 20 against the plunger 11, and when the latter is in its upper position, the gripper 18 seizes the bunch and the plunger 11 descends 45 again. The arm swings further over the mould 13 to deliver a finished cigar, held by the gripper 19. The arm then returns and swings with the bunch to the wrapping device 20, where said bunch is delivered.

In the meantime, the operator placed at 39 has chosen a tobacco leaf from a pack of such leaves and placed it on the cutting device 21, where a wrapper is cut out. This wrapper is then taken by the leaf carrier 23 which following the swinging movement of the arm 22 is brought to the wrapping device 20. Here the wrapper is automatically rolled around the bunch, and a finished cigar is obtained.

When the wrapping is finished the grippers 60 18 and 19 on the arm 16 approach the wrapping device again. The gripper 19 seizes the finished cigar, and a bunch brought forward from the roller 6 by the gripper 18 is then dropped at the wrapping device. Thereafter the arm 16 swings 65 once more away from the wrapping device passing the mould 13 to the belt 31, above which the gripper 19 drops the cigar near the driving roller 29, which rotates in such a direction that the upper part of said belt moves against the cup 37. If there is sufficient time for it, the dropped cigar is immediately picked up by the operator at 39 and placed in a container or possibly on another transport arrangement, leading to another receiving place.

75. However, if said operator because of the afore-

said reasons has not time to collect the cigars, the latter follow the upper part of the belt 31 to the cup 37 (as shown in Fig. 2), from where it can be picked up by the operator at 38, who in this case has plenty of time at her disposal, as she must regulate the speed of her work after that of the operator at 39. The cigars taken from the cup 37 can then either be stored in cases or boxes, or be brought by means of a convenient transporting device to another receiving place. This is implied as well in this case as at the primary receiving place, also if the expression "collect" is used. Due to the working conditions it may happen that all or part of the finished cigars are collected already by the operator at 39, or it may happen that the entire finished product is transported to the second receiving place.

I do not wish to limit my invention to the above mentioned details of construction as there are several other embodiments within the scope of the invention. The belt can thus be replaced by any other transport arrangement, and the belt or any other transport arrangement may be driven intermittently and, if this is considered suitable, the transport arrangement may be handled manually. The different and separately known parts of the cigar manufacturing machine, as buncher, pressing rollers, wrapper, cutting device and the transporting devices for bunches and wrappers, etc. can be developed in any way, as their construction forms no part of the invention.

What I claim as new and desire to secure by Letters Patent of the United States of America is:—

1. In a cigar manufacturing device having a plurality of manually served parts, means for transferring finished cigars to the proximity of one of said manually served parts, and means for transferring finished cigars from the same part to the proximity of another of said manually served parts.

2. In a cigar manufacturing device having a plurality of manually served parts, a stationary 120 wrapping device, means for transferring finished cigars from said wrapping device to the proximity of one of said manually served parts, and means for transferring finished cigars from the proximity of the same part to the proximity 125 of another of said manually served parts.

3. In a cigar manufacturing device having a manually served wrapper cutting device and a second manually served part, means for transferring finished cigars to the proximity of said 130 cutting device, and means for transferring finished cigars from the proximity of said cutting device to the proximity of the second manually served part.

4. In a cigar manufacturing device having a 135 manually served buncher and a second manually served part, means for transferring finished cigars to the proximity of said second part and means for transferring finished cigars from said second part to the proximity of the buncher.

5. In a cigar manufacturing device in combination, a manually served wrapper cutting device, means for transferring finished cigars to the proximity of said cutting device, a manually served buncher, and a device arranged to receive finished cigars in the proximity of said cutting device and transfer them to the proximity of the buncher.

6. In a cigar manufacturing device in combination, an automatically operating wrapping de- 150

vice, a manually served wrapper cutting device, a manually served buncher, a carrier for transferring finished cigars from the wrapping device to the proximity of the cutting device, and a device arranged to receive finished cigars in the proximity of said cutting device and transfer them to the proximity of the buncher.

7. In a cigar manufacturing device in combination, an automatically operating wrapping de-

10

vice, a manually served wrapper cutting device, a manually served buncher, a carrier for transferring finished cigars from the wrapping device to the proximity of the cutting device, and a carrier arranged to receive finished cigars in the proximity of said cutting device and transfer them to the proximity of the buncher.
